UNITED STATES PATENT OFFICE.

PETER NERNEY, OF ATTLEBOROUGH, MASSACHUSETTS.

SWIVEL FOR WATCH-CHAINS.

SPECIFICATION forming part of Letters Patent No. 295,577, dated March 25, 1884.

Application filed February 1, 1884. (No model.)

To all whom it may concern:

Be it known that I, PETER NERNEY, of Attleborough, in the county of Bristol and State of Massachusetts, have invented a new and useful Improvement in Swivels for Watch-Chains; and I do hereby declare the following specification, taken in connection with the accompanying drawings, forming a part of the same, to be a description thereof.

10 This invention relates to a swivel for watch-chains; and it consists in certain features of construction, as hereinafter set forth.

15 Referring to the drawings, Figure 1 represents a front view of the swivel with the bow thereof closed, as when connected to a watch-ring. Fig. 2 shows the same with the bow open to allow a watch-ring to be connected. Fig. 3 represents a central vertical section of Fig. 1. Fig. 4 shows in perspective the stem member with a portion of the bow secured thereto. Fig. 5 represents in perspective the neck member with the remaining portion of the bow secured to its head. Fig. 6 shows in perspective the swivel-sleeve with its attached ring.

20 A is the bow member, which is in two parts, *a* *a'*. The part *a* is secured to the upper end of the stem *B*, as shown in Figs. 3 and 4, and the part *a'* is rigidly attached to the head of the neck member *C*, as shown in Figs. 3 and 5. The neck member *C* is hollow, and has its head provided with a perforation, *c*, to receive the foot *a'* of the bow portion *a* when the bow is closed.

25 D is a bridge-piece, which stretches across the interior of the neck member *C*, and is secured to the walls thereof. The bridge-piece *D* is centrally perforated to form a bearing for the stem *B* and hold it at all times in axial alignment with the neck member.

30 E is the swivel-sleeve, which fits on the lower end of the stem *B*, and is furnished with an attached ring, *e*, to receive the watch-chain. The swivel-sleeve *E* is retained upon the stem *B* by a headed pin, *F*, which enters the lower end of the stem, and is secured thereto by solder. Preferably the stem *B* is made of hollow wire, to furnish a cavity into which the shank of the pin *F* can be inserted, as shown in Fig. 3; but the stem may be solid and have a hole drilled into its lower end to receive the pin-shank.

35 G is a spiral spring, which surrounds the stem *B*, and bears at its lower end upon the sleeve *E* and at its upper end upon the bridge-

piece *D*, thereby pressing the neck member *C* upward over the foot *a'* of the bow portion *a* and locking the bow in a closed position. The neck member *C* is mounted on the stem *B*, so as to be capable of longitudinal and rotary movements.

40 When it is desired to open the bow to admit or to release the watch-ring, the neck member *C* is depressed on the stem by the fingers until the foot *a'* of the bow portion *a* passes out of the perforation *c* in the head of the neck member. The neck member is then partially rotated to carry the bow portion *a'* to one side, as shown in Fig. 2, when the watch-ring may be inserted or withdrawn. 45 The bow is closed by turning the neck so as to bring the bow portion *a'* under the portion *a*, and then releasing the neck, when the spring *G* will raise the neck and its bow member *a'* and cause the foot *a'* of the bow portion *a* to 50 pass into the perforation *c* in the head of the neck, and thereby lock the bow in a closed position.

55 Although I prefer to make the stem *B* of hollow wire, and to employ the headed pin *F* to hold the sleeve *E* upon the stem, yet a circular plate covering the lower end of the sleeve may be soldered to the lower end of the stem for such purpose; or the lower end of the stem may project beyond the sleeve and be headed over thereon to retain the sleeve on the stem, as will be readily understood.

I do not claim, broadly, a swivel having a bow member capable of being turned, and having a neck member mounted so as to be movable on the stem, and actuated by a spring to lock the bow member in a closed position.

60 What I claim, and desire to secure by Letters Patent, is—

65 As an improved article of manufacture, a swivel composed of a stem *B*, having a bow portion, *a*, rigidly secured thereto, a neck member, *C*, having the remaining bow portion rigidly secured to its head, and said head provided with a perforation, *c*, to receive the foot 70 of the bow portion *a*, the bridge-piece *D*, secured to and within the neck member *C*, the swivel-sleeve *E*, having a ring attached thereto and secured upon the stem, as described, and the spiral spring *G*, mounted on the stem 75 and bearing against bridge-piece *D* and the sleeve *E*, substantially as set forth.

Witnesses: PETER NERNEY.

EDSON SALISBURY JONES,

HENRY J. STAPELTON,
